UNITED STATES PATENT OFFICE.

LOUIS LENARD, OF CHICAGO, ILLINOIS.

EXTENSION-TABLE.

1,275,948.

Specification of Letters Patent. Patented Aug. 13, 1918.

Application filed April 28, 1917. Serial No. 165,130.

To all whom it may concern:

Be it known that I, LOUIS LENARD, a subject of the Emperor of Austria, residing at Chicago, in the county of Cook and State 5 of Illinois, have invented certain new and useful Improvements in Extension-Tables, of which the following is a specification.

My invention relates to improvements in extension tables.

10 One of the objects of my invention is to provide an extension table within which the supplementary leaves are contained and to which they are inseparably attached, preferably, in a suitable receptacle below the 15 outwardly movable sections of the top, when said sections occupy adjacent positions, as when the table is contracted or closed, without the interposition of the extension leaves.

Another object of my invention is to provide 20 means whereby the longitudinally extendible parts may be moved with a minimum of effort and without the interposition of a great deal of friction.

Other and further objects of my invention 25 will become readily apparent, to persons skilled in the art, from a consideration of the following description when taken in conjunction with the drawings, wherein:—

Figure 1 is a plan view of a table, of the 30 round type when the top parts are not extended, showing parts in section.

Fig. 2 is a section, taken on line 2—2 of Fig. 1.

Fig. 3 is an enlarged section, showing a 35 portion shown in Fig. 2.

Fig. 4 is a section taken on line 4—4 of Fig. 3.

Fig. 5 is a longitudinal central section, taken on line 5—5 of Fig. 1, but showing the 40 supplementary leaves unfolded and in place, in the same horizontal plane with the segment members.

Fig. 6 is an isometric perspective view showing one set or pack of leaves folded 45 and in the position they occupy in the table, when the latter is closed or contracted to its smallest dimensions.

Fig. 7 shows the pack of leaves reversed and elevated on its supporting hinge bar, 50 and two of the leaves raised in the act of placing them in the same plane with the movable sections of the top.

Fig. 8 shows a further development of the 55 operation of unfolding the pack.

Fig. 9 is a view similar to that shown in Fig. 1, but showing a square top table.

Fig. 10 shows an elevation of the table extended.

Fig. 11 is an enlarged section taken on line 11—11 of Fig. 9.

In all the views the same reference characters are employed to indicate similar parts.

15 is the table top base having a rectangular central perforation 16 within which to contain the extension leaf packs and to 65 which is attached, at its under surface four legs 17, 18, 19 and 20. The legs are braced together, near their bottom ends, by a brace 21 and are preferably mounted upon rollers or casters 22. A bar 23 extends across the 70 opening 16 and holds the opposite sides of the table top base parts 15 together.

Extending across the opening 16, to one side of its axis or center of the table is a bar 24 secured in blocks 25 and 26. Two 75 packs or sets of extension leaves, 27 and 28, there being four leaves in each pack, are hinged to and slideable on the bar 24 by means of hinge cleats 29, so that each of the sets 27 and 28 may be rotated on and 80 raised to a higher plane by the bar 24. Each set consists of four leaves, 30, 31, 32 and 33. The leaves 30 and 31 are hinged together at their ends, as at 34 and the leaves 32 and 33 are hinged together at their ends, 85 as at 35. The leaves 31 and 33 are hinged together at their side edges, as at 36, so that to unfold the leaves, as shown in Fig. 6, the two leaves 32 and 33 are lifted, as shown in Fig. 7 on the hinges 36 and laid out flat so 90 that the end edges, farthest removed from the hinge portion, will lie in the same plane with the edges of the movable portions of the table top 40 and 41, as shown by dotted lines in Fig. 1. The sections of each set of 95 leaves are then pushed together so that the dowel pins 42 and 43, as shown projecting from the leaf 30, will enter registering dowel holes in the leaf 32, thereby holding and maintaining them in the same longitudinal 100 plane. The leaf 30 and 30^a of the respective sets, are each provided with a downturned support 44, which rests upon the cross bar 39 that extends at one edge transversely of the opening 16 in the table base 15.

105 The parallel slide bars for supporting and guiding the semi-circular segments 40 and 41 of the longitudinally movable sections of the table top, are preferably to be made of metal; each table top segment being provided with two parallel sliding bars which are substantially duplicates in every respect,

with the exception that one is preferably right handed, and the other is left handed, so to speak, that is to say, the flange of both the angle bars of a pair projects outwardly. 5 With this exception they are alike and therefore I will describe one and this description will apply to all. A fixed track for the parallel slide bars 45, of which there are two, each consists of a U-shaped member providing vertical side walls or limbs 46 and 47, which are substantially parallel, and which have their upper longitudinal edges inturned and downturned, as at 48 and 49 and provided with a connecting floor 50. The relatively stationary bar, thus provided, extends, preferably, the full length of the table top base and is secured thereto by suitable means. The coöperating angle bar 51, a pair of which is secured to each of the segments 40, 41, respectively, of the table top, is provided with a leg or flange 52 in a vertical plane, and a leg or flange 53, which is in a longitudinal plane, at right angles thereto. The latter flange 53 is secured directly to the table top segment, the flange 52 is preferably wider, near its inner end, as at 54, and carries on its extreme wider or inner end two ball bearing roller pulleys 55. These pulleys are circumferentially grooved, 30 as shown at 56, within which the downturned portions 48 and 49 of the members 46 and 47, respectively, are included. Secured to the lower portion of the wider part 54, of the sliding bars 51, is another pair of ball bearing pulleys 58 having a smooth face, roll upon the floor 50, of the relatively stationary sliding member 45. Another pair of ball bearing pulleys 60 may advantageously be secured to the narrow portion of the 40 bar 51, have a smooth face adapted to roll upon the lower surface of the downturned portions 48 and 49 of the members 46 and 47. Located near the outer end of the members 46 and 47 and secured to each are another pair of ball bearing pulleys 61, which are grooved similarly to the pulleys 55, to receive the lower edge of the narrow portion of the sliding bar 51. Now it is manifest that when either top segment, 40 or 41 of the 45 table is moved outwardly or inwardly, in the act of extending or contracting the top dimensions of the table, that the bar 51 connected to the respective segments of the table top, will slide with very little friction within the respective members 46 and 47 of the stationary portions of the sliding bars owing to the ball bearing construction shown. To permit the bars 51 to slide freely without interference, I provide a means for 50 lowering or vertically displacing the skirt 62 of the table top. The skirt 62 is round and neatly surrounds the base portion 15 of the table top. It is supported by rollers 63 which enter grooves 64 made in the inner 65 surface of the skirt. There are preferably

four rollers 63 so as to support the skirt 62 at four points. The grooves 64 are shaped, as shown in dotted lines in Fig. 5, they extend circumferentially of the skirt 62, one terminal portion of which is in a higher plane than the other terminal portion so that when the skirt 62 is rotated it will be raised or lowered, owing to this fact, as the case may be. In Fig. 5 the roller 63 is shown in the upper portion of the groove 64 and the skirt is shown lowered to its greatest extent so that the slides 51 will conveniently pass over the top of the skirt. Now when both sets of the leaves 31 and 33 inclusive are folded into packs and reversed and thereby lowered below the plane containing the top sections, as shown in Fig. 2, the segments 40 and 41 may be pushed together, into their normal positions. This movement will carry the bars 51 within the confines of the skirt 62, after which the skirt may be rotated, by which act it will move upwardly into a vertical plane, shown in dotted lines in Fig. 2. In this position the segments 40 and 41, of the table top, may not again be moved out until the skirt is again lowered, by rotating it to a slight extent in the opposite direction for the purpose described. This serves as a means for holding the segments together, but as a supplementary means, I prefer to place near the outer edge of each of the leaf segments 40 and 41, and depending from the lower edge thereof, a roller 65, which enters a circumferentially extending groove 66, when the skirt 62 is in its highest position with its upper edge substantially in contact with the lower edge of the segment 40 and 41, so that when the skirt is rotated for the purpose of raising it, the engagement of the inner surface of the skirt with the roller 65 will tend to firmly hold the confronting edges of the segments 40 and 41 tightly together. 95

In Figs. 9 and 10 I have shown a square table. In a square table there is considerably more space for the insertible leaves, and therefore it may contain three or more sets, as shown in these figures, which are operable and unfoldable in a similar manner. 105

In this particular square table embodiment the side portions of the skirt 62^a are fixed to the table base and the end portion 62^b may be secured directly to the table top sections so that when the table is extended the end portions 62^b move outwardly with the respective sections. This gives room for the slide bars 51^a to move outwardly and provides a finish by the continuation of the skirt, when the table is closed or contracted. 115

In Fig. 11 I have shown a slightly different form of stationary slide member 45^a, of the parallel sliding bars, in which this member is preferably made of a single piece. With this exception it is substantially the same as that heretofore described. 125

A button 68 may be secured to the cross bar 69 to hold the leaf packs 27 and 28 firmly in place when they are folded within the space provided in the table base 15.

5 While I have herein shown a single preferred embodiment of my invention with a slight modification thereof, it is manifest to persons skilled in the art that many changes and other modifications may be made within 10 the scope of the appended claims.

Having described my invention, what I claim is:—

15 1. An extension table comprising two oppositely slideable outwardly movable top sections; parallel slide bars connected to the underside of each section and extending inwardly; a top-skirt normally in the path of said bars, movable from said path to permit extension of said top sections, and leaves 20 folded normally under said sections adapted to be raised and fill the space between said separated sections.

25 2. An extension table comprising two movable top sections; parallel slide bars connected to the underside of each section and extending inwardly; a top-skirt normally in the path of said bars, rotatable to move it below the path of said bars to permit extension of said top sections, and leaves 30 folded normally under said sections adapted to be raised and fill the space between said separated sections.

35 3. An extension table comprising two slideably movable top sections; parallel slide bars connected to the underside of each section extending inwardly and normally within the table-skirt when the table is closed; a rotatable top-skirt normally in the path of said bars, and guides to lower the skirt out 40 of the path of said bars when said skirt is rotated, and leaves normally folded together

and located below said sections, adapted to be unfolded and raised to fill the space between said sections.

4. In combination in an extension table, 45 having a table top base, an outwardly movable top section supported on said base; a pack of four extension leaves, hinged together and foldable in a stack, one upon the other, and means, at one side of the axis of 50 the table, to which one leaf of the said pack is hinged, and upon which it is longitudinally slideable, whereby when the pack is opened each leaf thereof lies in the horizontal plane with the outwardly movable top 55 sections, and said hinge means permitting the extended leaves of the pack to be bodily slid when the movable top sections are moved into contact therewith.

5. In combination in an extension table, 60 having a table top base, which is centrally open and longitudinally movable top sections supported on said base; a pack of four extension leaves hinged together and foldable, one upon the other, in a stack, and contained within the open part of said top base when folded, and means at one side of the axis of the table extending across said opening to which one leaf of said pack is hinged 65 and upon which it is longitudinally slideable, 70 whereby each leaf of the pack lies in a plane below the longitudinal plane of the longitudinal movable section when the table is closed and in the same horizontal plane with the outwardly movable top section when the 75 pack is unfolded, and said hinge means permitting the extension leaves of the pack to be bodily slid when the table top sections are moved into contact therewith.

In testimony whereof I hereunto set my hand.

LOUIS LENARD.
